(57) CLAIM

The ornamental design for a wedge shoe, as shown and described.

DESCRIPTION

FIG. 1 is a perspective view of wedge shoe showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The texture lines and broken lines on the wedge shoe are for the purpose of illustrating portions of the shoe and form no part of the claimed design.
